Primary Examiner — John Windmuller(57) **CLAIM**

The ornamental design for a control module for television, as shown and described.

DESCRIPTION

FIG. 1 is a front elevational view of a control module for television showing our new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top, front and left side perspective view thereof; and,

FIG. 8 is a top, front and left side perspective view showing the control module for television linked with a wall-mounting type television in a use state.

The broken lines in the drawings illustrate portions of the control module for television which form no part of the claimed design.

The broken lines in FIG. 8 depicting the wall-mounting type television also form no part of the claimed design.
